GLIDER

Morton Pearlstine, Cynwyd, Pa.

Application November 17, 1953, Serial No. 27,640

Term of patent 14 years

(Cl. D15—11)

The figure is a perspective view of the glider showing my new design, the back of the glider seat being of conventional design.

The dominant features of the design reside in the portions shown in full lines.

I claim:

The ornamental design for a glider, substantially as shown and described.
